[57] **CLAIM**

The ornamental design for a convertible crib in bed configuration, as shown and described.

DESCRIPTION

FIG. 1 is a perspective view of a convertible crib in bed configuration;

FIG. 2 is a front elevational view;

FIG. 3 is a rear elevational view;

FIG. 4 is a right side elevational view with the left side being a mirror image thereof;

FIG. 5 is a top plan view thereof;

FIG. 6 is an enlarged cross-sectional view taken along lines 6—6 to better illustrate the contours thereof; and,

FIG. 7 is an enlarged cross-sectional view taken along lines 7—7 to better illustrate the contours thereof.

The broken line showing of a mattress is certain of the figures is for illustrative purposes only, and forms no part of the claimed design.
